CLAIM

We claim the ornamental design for a back housing for a handheld electronic device, as shown and described.

DESCRIPTION

FIG. 1 is a back perspective view of a back housing for a handheld electronic device;

FIG. 2 is a back elevational view of the back housing;

FIG. 3 is a right elevational view thereof; and,

FIG. 4 is a left elevational view thereof.

The broken lines shown in the drawings are for the purpose of illustrating unclaimed portions of the back housing for a handheld electronic device and form no part of the claimed design.
